Patented Nov. 3, 1914.

UNITED STATES PATENT OFFICE.

FRANK E. SLOCUM, OF EL RENO, OKLAHOMA.

SHOE-FASTENER.

1,116,142.

Specification of Letters Patent. Patented Nov. 3, 1914.

Application filed January 26, 1914. Serial No. 814,564.

To all whom it may concern:

Be it known that I, FRANK E. SLOCUM, a citizen of the United States, residing at El Reno, in the county of Canadian and State 5 of Oklahoma, have invented certain new and useful Improvements in Shoe-Fasteners; and I do hereby declare the following to be a full, clear, and exact description of the invention, such as will enable others skilled 10 in the art to which it appertains to make and use the same.

The primary object of this invention is to provide a novel method of lacing and fastening a shoe, which will be a great improvement 15 over the means now employed.

Another and more specific object of the invention is to provide a shoe having clips secured to meeting edges of the upper through which a lace is threaded, the strands 20 of the lace passing through apertures in a fastening plate, and the ends being permanently knotted together to engage behind the fastening plate and prevent the lace loosening or slipping.

With these and other objects in view as will be come more apparent as the description proceeds, the invention consists in certain novel features of construction, combination and arrangement of parts as will 30 be hereinafter more fully described and claimed.

For a complete understanding of my invention, reference is to be had to the following description and accompanying drawings, in which—

Figure 1 is a side elevation, showing a portion of a shoe laced and fastened in accordance with my invention. Fig. 2 is a longitudinal sectional view through the fastening plate. Fig. 3 is a transverse section through the fastening plate. Fig. 4 is a detail sectional view, showing one of the lacing clips. Fig. 5 is a detail fragmentary view of the shoe tongue, showing the means 45 provided for holding it in position.

Referring in detail to the drawings by numerals, 5 and 6 designate the edges of shoe upper, and 7 a plurality of clips which are secured thereto in spaced relation. Each 50 clip is formed of a strip of metal enlarged adjacent its ends and formed with apertures 8. The strips are U-shaped and are secured to the shoe by stitching or in any other preferred manner.

9 designates a lacing string which is run 35 through the clips 7 and which has its ends

secured to each other by being knotted, as indicated by the numeral 10.

A fastener 11, in the form of a preferably metallic plate of concavo-convex formation, is provided to secure the knotted ends of the 60 lacing strings and hold the edges 5 and 6 of the upper in proper relation. The plate is formed with a pair of openings 12 and with a recess 13 which is connected with the upper edge of the plate by a restricted passage 14. The recess 13 extends transversely across the plate 11 adjacent to the upper edge thereof and is arranged centrally between the side edges of the plate.

In lacing and fastening a shoe, the lace is first run through the clips 7 and through the openings 12 in the plate 11 and then knotted as before described. The knot is a permanent one and retains the fastening plate on the lace. The lace is of sufficient length to allow the edges 5 and 6 of the two uppers being spread sufficiently to easily put the shoe on and then by drawing upwardly on the knot, the lace is tightened. The lace 70 may be wound around and attached to the fastener in various ways, and for the purpose of illustration, I have shown the two strands as passing outwardly through the openings 12, then through the openings 13 and downwardly behind the plate. They are 75 then brought forwardly and upwardly across the front side of the plate and sprung into the recess 13 through the passage 14. This brings the knot 10 behind the plate 80 and since the knot is larger than the opening 13, it will not slip therethrough and can only be removed by bringing the lace through the passage 14. The portions 15 of the plate 11, which are formed by the opening 13 and 85 passage 14, are somewhat springy and will yield sufficiently to allow the lace to be easily inserted between their terminals.

From the foregoing description taken in connection with the accompanying drawings, it will be apparent that I have provided a very simple and practical shoe lacing means and fastener therefor, which may be cheaply manufactured and which will be found much more convenient than the old 100 way of lacing and tying the shoe. The tongue 16 is formed adjacent its upper end with a pair of parallel longitudinal slits, forming a strap 17 which is connected to the tongue at its ends only, and the strands 110 of the lace 9 are carried behind the strap 17 and cross, as clearly illustrated. This ar-

angement serves to hold the tongue always in proper position, and constitutes an important feature of my invention.

Having thus described my invention, I

claim:

1. A fastening plate for shoe laces, said plate being formed with a pair of openings and with a recess, the recess extending transversely of the plate adjacent one edge thereof and communicating with said edge by a restricted passage.
2. A fastening plate for shoe laces, said plate being formed with a pair of openings

to receive the leads of a shoe lace, the plate being also formed adjacent its upper edge 15 with a transverse opening communicating with said upper edge by a restricted passage, whereby the string may be inserted into the recess to dispose the knot on one side thereof.

In testimony whereof I affix my signature in presence of two witnesses.

FRANK E. SLOCUM.

Witnesses:

WALTER H. MARTIN,
EARL BEEBE.
